(57) **CLAIM**

We claim the ornamental design for a "LED lighting apparatus," as shown and described.

DESCRIPTION

FIG. 1 is a front perspective view of a LED lighting apparatus showing the new design;

FIG. 2 is a front view of the LED lighting apparatus of FIG. 1;

FIG. 3 is a rear view of the LED lighting apparatus of FIG. 1;

FIG. 4 is a left side view of the LED lighting apparatus of FIG. 1;

FIG. 5 is a right side view of the LED lighting apparatus of FIG. 1;

FIG. 6 is a top view of the LED lighting apparatus of FIG. 1;

FIG. 7 is a bottom view of the LED lighting apparatus of FIG. 1; and,

FIG. 8 is a front perspective view of the LED lighting apparatus of FIG. 1 shown in use with the light emitting part in diagonal line.

The broken lines shown on the drawings depict portions of the head for a street lamp that form no part of the claimed design.
